US0D1106082S

(12) **United States Design Patent** (10) **Patent No.:** **US D1,106,082 S**
(45) **Date of Patent:** **** Dec. 16, 2025**

(54) **END EFFECTOR**

(71) Applicant: **ASM IP Holding B.V.**, Almere (NL)

(72) Inventors: **Masashi Nakano**, Tama (JP); **Senthil Arasu Subas Chandra Bose**, Chandler, AZ (US)

(73) Assignee: **ASM IP Holding B.V.**, Almere (NL)

(**) Term: **15 Years**

(21) Appl. No.: **29/992,214**

(22) Filed: **Mar. 6, 2025**

(51) LOC (15) Cl. **13-03**

(52) U.S. Cl.

USPC **D13/182**; D13/154

(58) **Field of Classification Search**

Assistant Examiner — Denis Houyoux

(74) Attorney, Agent, or Firm — Banner & Witcoff, Ltd.

(57) **CLAIM**

The ornamental design for an end effector as shown and described.

DESCRIPTION

FIG. 1 is a top right perspective view of an end effector showing our new design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof; and,

FIG. 8 is a bottom left perspective view thereof.

1 Claim, 8 Drawing Sheets
